UNITED STATES PATENT OFFICE.

JULIUS EDGAR LILIENFELD, OF WATERBURY, CONNECTICUT, ASSIGNOR OF ONE-HALF
TO WILLIAM H. BRISTOL, OF WATERBURY, CONNECTICUT.

AUTOELECTRONIC DEVICE.

Application filed January 28, 1922. Serial No. 532,353.

To all whom it may concern:

Be it known that I, JULIUS EDGAR LILIENFELD, a citizen of Poland, and a resident of Waterbury, in the county of New Haven and State of Connecticut, have invented certain new and useful Improvements in Auto-electronic Devices, of which the following is a specification.

The invention relates to an electron releasing device, embodying an "auto electronic" effect, that is to say a release of electrons due solely to an electric field, for example, a device of the nature set forth in my co-pending U. S. application, Serial No. 364,215, filed the 8th day of March, 1920. In this application there is disclosed a sealed envelope or vessel, evacuated to such a high degree that ionization is substantially absent, said vessel enclosing also unheated electrodes separated by a gap sufficiently short to permit the starting of a discharge of electrons between said cold electrodes upon the application of a suitable potential. The present invention, however, relates to a novel form of the electron releasing cathode, particularly as to its shape and the metal comprising same, and to the method of producing such cathode.

It has for its object in an "autoelectronic" device of this character, to provide an "auto-cathode" or member releasing electrons solely under the influence of an electric field and of such special design and composition as to admit of employing much lower voltages than have heretofore been possible in the use of highly evacuated containers with cold electrode or electrodes. A very considerable reduction of the voltage may be obtained by making the cathode of an extremely fine wire and providing a superfine point on it—not by mechanical means, however, but by chemical action. I have found that by employing for the cathode such metals as are found at the most electro-positive end of the scale, as the alkali metals and alkaline earth metals, the voltage necessary to cause current to pass between cold electrodes, in the absence of any substantial ionization and with predetermined gap, is greatly reduced. The degree of reduction appears to be greatest with the most electro-positive metals—such as caesium, rubidium, potassium, sodium and lithium, while diminishing when approach-

ing the less electro-positive metals. The reduction, however, is still remarkable with the alkaline earth metals. Moreover, an alloy of two or more of said metals may be utilized for the production of a cathode. For example, in working with caesium, an admixture of potassium, sodium or other metal of higher melting point is useful to make the caesium harder and reduce the pressure of its vapor.

Moreover, the mere presence within the highly evacuated container of the metals set forth, as in causing same to be deposited in any part of the container, has a beneficial effect for some of the metal eventually finds its way to the cathode.

The invention contemplates, furthermore, a novel method for preparing an "auto-cathode" from these metals, which normally are not suitable for exposure to the atmosphere, in forming such cathode in the envelope after evacuating it to a high degree.

The nature of the invention, however, will best be understood when described in connection with the accompanying drawings, in which—

Fig. 1 represents a glass envelope, designed to be highly evacuated and provided with means for introducing metal.

Figs. 2 and 3 illustrate similar vessels provided with different means for introducing the metal.

Similar characters of reference designate corresponding parts thruout the several views.

Referring to the drawings, 10 designates a glass envelope or vessel which is designed to be evacuated, thru a suitable outlet which is subsequently sealed, as is well understood. An anode 11 and a cathode 12 are provided in the vessel 10, to cooperate in manner set forth in my co-pending application Serial No. 364,215, filed March 8th, 1920; but in accordance with the present invention, the cathode is a superfine point and also comprises a metal such as is found at the most electro-positive end of the scale.

Referring more particularly to Fig. 1, in addition to the two electrodes noted, there is further provided a pointed or sharp-edged blade member 15 in proximity to the anode and a similar member 16 in proximity to the cathode, said members being designed to provide bombarding electrons for their re-

spective electrodes to heat up same and free them from occluded gases in the evacuation of the vessel.

The cathode 12 has been shown as a fine wire, about one-tenth of a millimeter, with a superfine point, that is to say a point which under a magnification of several hundred diameters, still appears as a point. In accordance with the invention, this wire is to 10 be coated with a metal such as is found at the most electro-positive end of the scale, for example an alkali metal as caesium.

Such superfine points may be obtained of fine wire which has been employed as an 15 anode in an electrolytic process, or has been dipped into a suitable solvent until reduced to the necessary degree of fineness. If tungsten be used to receive the cathode coating, the tungsten wire may be dipped into 20 potassium nitrite. In the case of a glass or quartz support for the cathode coating, fluoric acid may be used to point the glass. Other means for obtaining fine points of 25 the wire consist in utilizing same as an electrode for a gas discharge, arc discharge, spark discharge, etc.

To effect the introduction of the cathode metal, which is subject to immediate oxidation, into the vessel 10 and its deposition on 30 the cathode 12, cathode metal 20, as caesium or for example another of the more volatile metals such as rubidium, potassium and sodium, or an alloy thereof, is placed in the outermost bulb of a series of connected 35 bulbs 21. These bulbs terminate in the vessel 10 thru a tube 22 having its outlet in proximity to the cathode. The metal is successively distilled from one bulb to the next, while sealing off the last empty bulb 40 so that, finally, a metallic deposit in a high state of purification and free of gases, will be produced within the vessel 10 and upon a portion of the cathode support 12, forming a coating thereon of caesium or of an 45 other metal found at the most electro-positive end of the scale and from which electrons may be projected at much lower voltages than have been heretofore possible.

Another means of introducing the cathode 50 metal to form the "autoelectronic" cathode is illustrated in Fig. 2. The metal 30, in this instance, as in the former case is successively distilled thru a series of bulbs 31 into a tube 32 surrounding the cathode support 33 and deposited thereon to form a suitable coating. Or, when the character of 55 the metal will permit of so doing, it may be melted and caused to run down thru the tube and over the cathode support, subsequently cooling and forming a solid coating 60 thereon.

A further expedient is set forth in Fig. 3, in which the cathode support 35 is shown surrounded by a cap member 36 having a 65 perforated tapered end thru which the sup-

port passes. The cap member 36 is designed to retain a capsule or disk of the cathode metal 37; and the member is then heated to evaporate said metal and cause it to be deposited on the cathode support 35. This 70 method is especially suitable for the less volatile metals such as calcium, strontium, barium and lithium; and the heating is effected by means of bombarding electrons discharged from an electrode 38 mounted in 75 the vessel in proximity to the cap, said bombardment serving also to drive out any occluded gases therein. By this expedient, only a slight amount of the cathode metal 80 condenses outside of the cathode point. This is a decided advantage as the electronic discharge will then not find a metallic coating from which gases would be set free thereby and affect the degree of vacuum and consequently the electron releasing effect. 85

In the use of the metals for cathodes as hereinbefore set forth, it has been possible to reduce the voltage required to such an extent so that the device becomes suitable for use as a detector or transmitter of electro-magnetic waves and for amplification 90 purposes.

I claim:—

1. An autoelectronic device, comprising a sealed envelope evacuated to such a high degree that ionization is substantially prevented, and containing a metal found at the most electro-positive end of the scale, and unheated electrodes therein, separated by a gap sufficiently short to permit of starting 100 the discharge therebetween upon the application of a suitable potential. 95

2. An autoelectronic device, comprising a sealed envelope evacuated to such a high degree that ionization is substantially prevented, and unheated electrodes therein, one of which comprises a metal found at the most electro-positive end of the scale, said electrodes being separated by a gap sufficiently short to permit of starting the 110 discharge therebetween upon the application of a suitable potential. 105

3. An autoelectronic device, comprising a sealed envelope evacuated to such a high degree that ionization is substantially prevented, and unheated electrodes therein, one of which consists of an alkali metal, said electrodes being separated by a gap sufficiently short to permit of starting the 120 discharge therebetween upon the application of a suitable potential. 115

4. An autoelectronic device, comprising a sealed envelope evacuated to such a high degree that ionization is substantially prevented, and unheated electrodes therein, one of which comprises caesium, said electrodes being separated by a gap sufficiently short to permit of the discharge therebetween upon the application of a suitable potential. 125

5. An autoelectronic device, comprising a 130

sealed envelope evacuated to such a high degree that ionization is substantially prevented, and unheated electrodes therein, one of which consists of a support coated with cæsium, said electrodes being separated by a gap sufficiently short to permit of starting the discharge therebetween upon the application of a suitable potential.

6. An autoelectronic device, comprising a sealed envelope evacuated to such a high degree that ionization is substantially prevented, and unheated electrodes therein, one of which consists of a pointed support coated with a metal found at the most electro-positive end of the scale, said electrodes being separated by a gap sufficiently short to permit of starting the discharge therebetween upon the application of a suitable potential.

7. An autoelectronic device, comprising a sealed envelope evacuated to such a high degree that ionization is substantially prevented, and unheated electrodes therein, one of which consists of a superfine support coated with a metal found at the most electro-positive end of the scale, said electrodes being separated by a gap sufficiently short to permit of starting the discharge therebetween upon the application of a suitable potential.

8. An autoelectronic device, comprising a sealed envelope evacuated to such a high degree that ionization is substantially prevent-

ed, and unheated electrodes therein, one of which consists of a superfine support coated with cæsium, said electrodes being separated by a gap sufficiently short to permit of starting the discharge therebetween upon the application of a suitable potential.

9. An autoelectronic device, comprising a sealed envelope evacuated to such a high degree that ionization is substantially prevented, and unheated electrodes therein, one of which consists of a superfine support coated with an alloy of cæsium and potassium, said electrodes being separated by a gap sufficiently short to permit of starting the discharge therebetween upon the application of a suitable potential.

10. An autoelectronic device, comprising a sealed envelope evacuated to such a high degree that ionization is substantially prevented, and unheated electrodes therein, one of which consists of a superfine support coated with an alloy of cæsium, potassium and sodium, said electrodes being separated by a gap sufficiently short to permit of starting the discharge therebetween upon the application of a suitable potential.

Signed at Waterbury, in the county of New Haven and State of Connecticut, this 26th day of January, A. D. 1922,

JULIUS EDGAR LILIENFELD.
